UNITED STATES PATENT OFFICE.

ERIK AUGUST BOLINDER, OF STOCKHOLM, SWEDEN.

METHOD OF MAKING BARRELS AND CASKS.

Application filed June 25, 1920. Serial No. 391,726.

To all whom it may concern:

Be it known that I, ERIK AUGUST BOLINDER, subject of the King of Sweden, residing at Jaktvarvsgrand 4, Stockholm, Sweden, have invented certain new and useful Improvements in Methods of Making Barrels and Casks, of which the following is a specification.

As is well known in the art of making barrels and casks, great difficulty has been occasioned in producing absolutely tight joints between the staves of the barrels, even if the casks were hooped very tight. Many endeavours have been made to improve on the methods; among them also grooving of the cask staves has been attempted. In bulging barrels, however, it has been necessary to confine the art to the use of a common rectangular or wedge-shaped groove and tongue joint, producing a comparatively tight engagement between the staves, it is true, but not capable of preventing the staves from being disjointed. Thus there would still remain the possibility of leaks occurring between the staves.

The present invention has for its purpose to facilitate the employment of a so called dove-tailed or similar tongue in making bulging barrels. The said kind of tongue possesses all qualifications for giving the desired result as regards tightness and durability, the same holding the staves securely together so as to prevent them from parting in a crosswise direction. The reason for not heretofore using such a tongue and groove in the ordinary bulging barrels, that is to say in barrels having their largest width at the middle and contracting toward the end portions thereof, is that no method could be devised for sliding the staves having different widths at the middle and the end portions thereof into engagement with each other. This difficulty has been removed by the present invention which thus makes it possible to produce barrels and casks of the ordinary bulging shape from staves with dove-tailed or similarly shaped tongues. Such barrels have many important advantages over others, one advantage being that they are easier to handle, and by the invention they are also rendered very strong, which is particularly desirable in cases where they are intended for long transportations of costly liquids.

The invention is primarily characterized by this that the staves provided with dove-

tailed or similarly shaped tongues and grooves are slid onto each other after first shaping them or their tongue or groove so that they will extend longitudinally along a curvature adapted to such assembly of the staves, for instance a circular arc. This is the principal feature of the invention, the latter, however, being further characterized by this that the edges of two adjacent staves adapted to be slid onto each other are located in a plane extending through the longitudinal axis of the barrel or the cask, or laterally of such axis.

The method is illustrated in the accompanying drawing, in which,

Fig. 1 shows two of the staves of the barrel, such stave being broadest at the middle and contracting toward the end portions thereof.

Fig. 2 shows one stave in an edge-view, and Fig. 3 the same in cross section. Fig. 4 shows to an enlarged scale the shape of the tongue as mostly used, or the so called dove-tailed tongue. Fig. 5 illustrates the way of sliding two such staves together upon their having been shaped after circular arcs with the same radius of curvature. Figs. 6 and 7 show a ready assembled barrel in elevation and a top plan view respectively. Fig. 8 shows barrel staves with dove-tailed tenons, the staves being curved in accordance with the common circular shape of the barrel.

In making the wall of the barrel, staves are used of a shape according to Fig. 1, the two longitudinal edges of each stave running along continuous curves. The difference of width at the middle of the stave and at the ends thereof is of course dependent on the more or less pronounced bilge of the barrel. The staves may be either somewhat arched in a crosswise direction in accordance with the circumference of the barrel which is generally of a circular shape, or they may be straight according to Fig. 4, in which latter case the edge of the stave is arranged somewhat obliquely to the surface of the stave. The two longitudinal edges of the stave are provided with a tongue 2 and a groove 3, and the profile of the tongue is selected so that the staves cannot be brought in engagement or pulled apart transversely. The tongue profile as disclosed in the drawing is dove-tailed, but it is evident that any other profile preventing the engagement or the pulling apart of the staves laterally may be employed. On the inside, near the ends,

the staves are provided with crozes 4 receiving the edges of the barrel heads. The crozes may be made before or after the staves are put together.

- 5 The staves formed according to Fig. 1 cannot be slid onto each other as long as they are flat. To facilitate the sliding together of the staves they are therefore shaped according to the invention so that they or their 10 tongues or grooves run in the longitudinal direction along a circular arc according to the Figures 2 and 5, both staves having the same radius of curvature. If the staves are of a flexible sort of wood, it is not necessary 15 that they be shaped exactly on a circular arc from the beginning, but they may then be given this shape approximately, after which, when sliding the staves together, they will 20 assume the proper form. The staves or the tongued edges thereof must be further made so that the edges to be slid together, and which are indicated for instance by the curved line A—B in Fig. 6, will be located in one and the same plane A—B (Fig. 7) 25 when the tongue of one stave is introduced into the groove of the adjacent stave. The said plane A—B forms an angle with the surface of the staves next to the edge. As a rule this angle is selected so that it will be 30 a right one so as to cause the plane A—B to coincide with the plane extending through the joint between the two staves and the longitudinal axis of the barrel. However, the angle selected may be smaller so that the 35 plane A—B will be located on one side of the longitudinal axis of the barrel or, perhaps, will form a small angle with this axis.

The staves may be tongued and grooved either before they are given the requisite 40 shape for sliding them together, or they may be shaped first and tongued and grooved afterward.

After the staves have been arched they may be readily slid together in the longitudinal direction according to Fig. 5. When two staves have been jointed in this way, a third stave, a fourth one and so on may be joined thereto, until the whole shell of the barrel is nearly ready and only a narrow 50 space remains between the free edges of the two outermost staves, such space being then filled in a special manner.

What I claim as new and desire to secure by Letters Patent of the United States is:— 55

A method of making barrels and casks having a larger circumference at the middle than at the two end portions consisting in employing longitudinally curved staves and shaping the longitudinal edges thereof in 60 the form of a circular arc, then forming the edges with interlocking tongues and grooves and finally inserting the tongues near the end of one stave in engagement with the groove at the opposite end of the adjacent 65 stave and sliding the staves longitudinally of each other to effect interlocking engagement thereof.

In testimony whereof I affix my signature in presence of two witnesses.

ERIK AUGUST BOLINDER.
